WEIGHT DEVICE

Selmer Roinestad, Kenosha, Wis., assignor to
 Scott & Williams, Incorporated, New York,
 N. Y., a corporation of Massachusetts

Application July 28, 1934, Serial No. 737,446

16 Claims. (Cl. 66—148)

This invention relates to means for securing fabric in position on the transfer rings used for placing previously knit rib tops on the needles of circular knitting machines and it is an object of this invention to provide a means of the type described which comprises a weight device suitable not only for use in positioning fabric on transfer rings but also for use in transferring such fabric from the transfer rings to the cylinder needles of circular knitting machines and in applying to the fabric the load or tension necessary to carry the fabric from the needles as it is knit. It is also an object of this invention to provide an improved point for use in transfer rings.

15 In the drawing—

Fig. 1 is a view partly in elevation and partly in section of a weight device constructed in accordance with this invention shown applied to a fabric on a transfer ring during the ravelling back of the excess fabric;

Fig. 2 is a view similar to Fig. 1 showing the points of the device shielded to prevent their engaging the fabric during the removal of the device from a fabric on a transfer ring;

Fig. 3 is a view similar to Fig. 1 showing the application of the device to the fabric during the transfer of the fabric from the transfer ring to the needles of a circular knitting machine; and

Fig. 4 is a top plan view of the device shown in Figs. 1 to 3.

With the introduction of the short rib tops for socks there has been considerable difficulty in attaching the usual loading or tensioning devices to the fabric as there is insufficient loose fabric to which the devices may be secured when the rib top is placed in position on the needles and the tension of this fabric of the short rib tops while in position on the transfer ring is such that considerable difficulty is encountered in keeping the loops on the points while ravelling back the excess fabric, particularly in the case of rib tops having elastic insertions to serve as garters.

As shown in the drawing a device constructed in accordance with this invention to overcome these difficulties comprises a cylindrical weight 1 which may be flanged, as at 2, and which is provided with a centrally projecting post or standard 4 slidably supporting a sleeve 6 enlarged at one end, as at 8, to serve as a handle. Confined on the standard 4 between the weight 1 and the sleeve 6 is a spring 10 which tends to force the sleeve away from the weight 1. Secured to the outer end of the sleeve 6 adjacent the enlarged end 8 is a disc 12 having a peripheral flange 14 and two circular rows of openings 15. Secured

to the weight 1 in a circle around the standard 4 is a row of spaced spring wires 17 which extend upwardly and outwardly to adjacent the disc 12 and provided with substantially inverted U-shaped hook ends having the side portions thereof parallel to the direction of movement of the disc 12 and normally projecting through radially disposed pairs of the openings 15 in the disc. The outer side portions 18 of the hook ends are pointed as at 19 and are of less length than the parallel inner portions 16 and also of less length than the distance through which the sleeve 6 is moved on the standard 4.

Attached to the disc 12 adjacent the center thereof are wires 20 having portions 22 which are bent to lie outside of the wires 17 so as to form handles or engaging portions to be grasped by the operator, as indicated in Figure 2, to reciprocate the disc 12 from the position shown in Figure 1, in which the points 19 are exposed, to the position shown in Figure 2 in which the points 19 lie above the disc 12 and are shielded by the peripheral flange 14.

The device is used in connection with a transfer ring in which the usual ring body 26 is provided with points 28 of U-shaped cross section having the sides thereof tapering from the shoulder 29 to merge with the point formed in the base of the U-section at 30. Projecting from the base of the U-section of each pin is an abutment 32 which serves to prevent the loops of the fabric being drawn from the points 28 after having been placed thereon by the tension under which the fabric is placed and particularly in the case of the short ribbed tops now in use where elastic 35 is knit or looped in the ribbed top in order to serve in place of garters.

With the fabric 33 placed in position on the points, as shown in Figure 1, the device is dropped through the opening in the fabric, the operator holding the enlarged end 8 of the sleeve 6 and the wires 17 serving to center the device so that the points 19 engage the fabric substantially uniformly from the points 28 throughout the circumference of the device. With the device thus in position the excess of the fabric may be ravelled back as indicated in Figure 1, the device holding the fabric in position and preventing the pull by the operator in ravelling back the fabric from withdrawing the fabric from the points. With the fabric ravelled back to the course upon the points 28 the operator, by grasping the handles 22 and the flange 2 and compressing the spring 10, as shown in Figure 2, will cause the disc 12 to travel on the wires 17 bringing the disc below

the points 19 and placing the flange 14 of the disc between the points 19 and the fabric 33 whereupon the device may be withdrawn from the fabric by a movement in the same direction as when placing the device in position.

With the fabric in position on the points and ravelled back, as shown in Fig. 2, the transfer ring is then inverted and the points 28 placed over the needles N of a circular knitting machine 10 in the usual manner, the transfer ring being positioned with respect to the needles as shown in Figure 3. Thereupon the device is dropped through the transfer ring to engage with the fabric, the weight of the device aiding in moving 15 the loops of the fabric down the points 28 and past the abutments 32 onto the needles N and below the latches of the needles. In those cases where tension of the fabric is sufficient to hold the fabric upon the points of the transfer ring even with the weight of the device thereon the 20 length of the device is such that it may be readily grasped by reaching upwardly through the needle cylinder in the usual way to draw down upon the fabric and in this way transfer the fabric 25 from the transfer ring to the needles. With the device positioned as in Figure 3 and the transfer ring removed the remainder of the stocking is knit in the usual manner and upon discharge or delivery of the finished stocking from the knitting machine the device will be withdrawn from 30 the stocking by operating the handles 22 to compress the spring 10 in the same manner as in withdrawing the device from the fabric in Figure 2. This releases the points 19 from the fabric 35 and places the flange 14 of the disc 12 in position to prevent the points engaging the fabric while the device is being drawn from the stocking.

What is claimed is:—

1. In a device of the class described, a weight, 40 a circular row of points attached to said weight, a standard carried by said weight, a flanged disk movably mounted on said standard and having openings to receive said points, resilient means for holding said disk in a position in which the 45 points are exposed and means to operate said disk to a position in which the points are shielded.

2. In a loading device for a fabric supported by circular supporting means, means to engage the supported fabric by movement of the device 50 in one direction with respect to the fabric and a shield movable relatively to the fabric engaging means to disengage the fabric from said means, said shield preventing engagement of said means with said fabric during removal of the device 55 from the fabric by movement of the device in the direction in which it was inserted.

3. In a device for weighting short tops supported by circular supporting means, a weight, 60 points attached to said weight and adapted to engage said top by movement of the device through the top and a shield movable relatively to the points to disengage the short tops from said points, said shield preventing engagement of said points with said short tops during removal of the device from the short tops by movement of the device in the direction in which it was inserted.

4. In a device for weighting short tubular fabric supported from one end by circular supporting 70 means, a weight, a ring of outwardly positioned points attached to said weight and adapted to engage said fabric by insertion of the device in the opening of the fabric, a shield movable relatively to said points to disengage the fabric from said points, said shield preventing engagement of said

points with said fabric during removal of the device from the fabric by movement of the device in the direction in which it was inserted.

5. In a device of the class described, a weight for applying load to a tubular fabric, means for distributing the load circumferentially of the fabric and means for shielding said distributing means which disengages said distributing means from the fabric in moving to shielding position.

6. In a loading device for a fabric supported 10 by circular supporting means, means to engage the supported fabric by movement of the device in one direction with respect to the fabric and means to shield said engaging means during a 15 disengaging movement of the device in the direction in which it was inserted.

7. In a device for weighting short tops supported by circular supporting means, a weight, 20 points attached to said weight and adapted to engage said top by movement of the device through the top and means to guard said points during disengaging movement of the device in the direction in which it was inserted.

8. In a device for weighting short tubular fabric supported from one end by circular supporting 25 means, a weight, a ring of outwardly positioned points attached to said weight and adapted to engage said fabric by insertion of the device in the opening of the fabric and means to shield said points during disengaging movement 30 of the device through the opening of the fabric in the direction in which it was inserted.

9. In a weight device for holding under tension fabric extending from said device to a supporting means, a group of circumferentially arranged relatively fixed points, a weight connected to said points to be supported thereby and means having a position in which said points are engageable with a fabric and arranged for movement to a position preventing engagement of a 40 fabric by said points to disengage the fabric from the points.

10. In a device for applying load to a fabric, a weight, a circular row of similarly directed points attached to said weight, a standard carried by said weight, a disk movably mounted on said standard, means yieldingly holding said disk in a position in which said points are exposed for engagement with a fabric and means to operate said disk to a position in which said points are shielded against engagement with a fabric, said disk being arranged to force fabric from said points in moving to the shielding position.

11. In a weight device for holding under tension a fabric extending from said device to a supporting means, a group of relatively fixed circumferentially arranged normally engageable points for engaging the fabric, a weight connected to said points and means for forcing fabric from the points.

12. In a weight device for holding under tension a fabric extending from said device to a supporting means, a group of relatively fixed circumferentially arranged points for engaging the fabric, a weight connected to said points, means for forcing fabric from the points, said means having a position shielding said points and means for holding said shielding means with said points normally exposed.

13. In a weight device for holding under tension a fabric extending from said device to a supporting means, a group of relatively fixed circumferentially arranged normally engageable points for engaging the fabric, a weight con- 75

nected to said points and means for positively forcing a fabric from said points, said means preventing said points from engaging a fabric while held at the limit of its fabric disengaging movement.

- 5 14. In a device of the class described, a weight for holding under tension a fabric extending from said device to a supporting means, means for applying the load of the weight circumferentially 10 on the fabric and means for positively forcing the fabric from said load applying means, said disengaging means being positioned to prevent said load applying means engaging the fabric upon completion of the disengaging movement.
- 15 15. In a device for holding fabric under tension, a weight, a plurality of upright members mounted in a circle on said weight, said members having reversely bent end portions forming fab-

ric engaging points and a disc movably mounted on said members, said disc having openings to receive said reversely bent end portions and being movable from a position engaging said end portions to a position clear of said end portions.

- 5 16. In a device for holding fabric under tension, a weight, a plurality of upright members mounted in a circle on said weight, said members having reversely bent end portions forming fabric engaging points, a disc movably mounted on 10 said members, said disc having openings to receive said reversely bent end portions and being movable from a position engaging said end portions to a position clear of said end portions and a spring for holding said disc in engagement with 15 said end portions.

CERTIFICATE OF CORRECTION.

Patent No. 2,047,888.

July 14, 1936.

SELMER ROINESTAD.

It is hereby certified that error appears in the printed specification of the above numbered patent requiring correction as follows: Page 2, second column, line 15, claim 6, strike out the article and syllable "the di-"; and that the said Letters Patent should be read with this correction therein that the same may conform to the record of the case in the Patent Office.

Signed and sealed this 15th day of September, A. D. 1936.

Henry Van Arsdale
Acting Commissioner of Patents.
